UNITED STATES PATENT OFFICE.

HENRY D. EBERT, OF BALDWINSVILLE, MASSACHUSETTS.

STAMP OR TICKET VENDING MACHINE.

971,531.

Specification of Letters Patent.

Patented Oct. 4, 1910.

Application filed July 20, 1909. Serial No. 508,559.

To all whom it may concern:

Be it known that I, HENRY D. EBERT, citizen of the United States, residing at Baldwinsville, in the county of Worcester and State of Massachusetts, have invented certain new and useful Improvements in Stamp or Ticket Vending Machines, of which the following is a specification.

This invention relates to an apparatus for vending postage stamps, postal cards, tickets, or other articles capable of being arranged within the apparatus in the form of a strip or ribbon, said articles being separated by perforations or weakening lines in such a manner as to permit the article to be torn from or broken away from the strip with which it is connected.

The object of the invention is to provide a simple and efficient apparatus of this character which will feed one or more stamps, tickets or other articles, upon the insertion of a certain prescribed coin or coins, and the particular object is to provide an apparatus which is capable of adjustment for the use of any desired coin, or for the use of a plurality of coins, and which will remain inoperative until the coin or coins of the required dimension are inserted.

A further object is to provide a mechanism in which the stamps, tickets or other articles may be carried in the form of a folded strip and be successively delivered as desired.

A still further object is to provide means whereby the coin opening may be closed when the articles to be vended have been exhausted.

Further advantages depend upon the particular arrangement of parts and details of construction, as will be set forth in the accompanying specification and more particularly stated in the appended claims.

For a full understanding of the invention and the merits thereof, and to acquire a knowledge of the details of construction, reference is to be had to the following description and accompanying drawings, in which:

Figure 1 is a side view of my vending machine, parts being in section; Fig. 2 is a like view from the opposite side of the machine; Fig. 3 is a perspective enlarged detail showing the locking wheel and its connected parts; Fig. 4 is a fragmentary detail showing the means whereby the conducting chute is supported on the standards; Fig. 5

is a detail perspective view showing the T-shaped locking pin; Fig. 6 is a vertical section through the case and transverse to the section in Fig. 1, showing the position of the various parts; Fig. 7 is a horizontal section; Fig. 8 is an enlarged fragmentary side elevation of the locking wheel and connected parts; Fig. 9 is a perspective view of the discharging rollers and their gearing; Fig. 10 is an inner face view of the discharging rollers and the frame in which they are mounted; Fig. 11 is a perspective fragmentary view showing the coin chute and its coin-testing mechanism; Fig. 12 is a perspective detail view showing the stop for preventing the introduction of coins when the machine is empty; Fig. 13 is a perspective detail of the stop detached from its supporting mechanism; Fig. 14 is a fragmentary horizontal section of the front wall of the case, showing a portion of the coin chute and the stop; and, Fig. 15 is a detail perspective of the yoke which supports the discharging rollers.

Corresponding and like parts are referred to in the following description and indicated in all the views of the drawings by the same reference characters.

Referring to the drawings, 2 designates a case within which the mechanism and stamp compartment are supported. The exterior of the case, upon its front face, is provided with the coin opening 3 having the form of a vertical slot, the stamp delivery slot 4 and the actuating knob 5.

Mounted upon the floor of the case are the opposed standards 6 of any desired construction, having in their upper ends bearings for a shaft 7. The upper end of one of the standards is provided with a transverse bar 8 upon which is supported the opposed approximately triangular frames 9, the base bars of which extend across on a level with the upper ends of the standards 6. Mounted upon the end of the shaft 7 and located between the opposed triangular frames 9 is the locking wheel 10 having in its circumference the radial notches 11. The outer face of the wheel between the notches is ground away so as to form a series of teeth 12 having ratchet or cam-like faces. Also mounted on the shaft 7 at one side of the wheel 10 is the ratchet wheel 13, and upon the shaft 7 is mounted the bifurcated bar 14. The rear end of this bar is connected by a spring 15 with the cross bar 16 on the standard. The

ratchet wheel 13 is mounted between the bifurcated bar so that the bar straddles the ratchet wheel. Pivoted within the closed end of the bifurcated bar is the pawl 17 which is pressed by the spring 18 into engagement with the ratchet wheel 13. The bifurcated bar is guided in its movement by a guide plate 19 mounted upon a cross bar 20 which is attached to the standards and projects upward from the side thereof. This guide plate is cut away as at 21 so as to receive the bar 14 and to limit its movement as well as guide the bar in its travel and hold it from any lateral play. The extremity of the bar 14 is reduced as at 22, and attached thereto is a chain 23 which extends downwardly and is attached to a small winding drum on a shaft 25. This shaft is mounted in bearings on a bracket 26 and extends out through the front wall of the case and carries the knob 5. Thus, upon turning the knob 5, the drum 24 will be rotated and wind up the chain 23 which will thus depress the bifurcated bar or lever 14, and this, through its pawl, will rotate the ratchet wheel 13, thus rotating the shaft 7 and rotating the wheel 10, provided this wheel is unlocked by the coin-operated mechanism, as will be later described.

30 Mounted upon the extremity of the shaft 7 is the gear wheel 27 which gears with a pinion 28 on a shaft 29 which is carried in a vertical frame 30. This shaft carries upon it a fiber roller 31. Also mounted in the frame 30 and immediately beneath the roller 31 is the roller 32 on a shaft 33 which shaft carries the pinion 28 and is driven therefrom. Thus, upon a rotation of the gear wheel 27, the roller 31 will be turned downward and outward, while the roller 32 will be turned upward and outward. The stamp or strip to which the stamp is attached is drawn out by the rotation of these rollers. In order to cause the rollers to grip the strip upon which the stamp or other object is formed, I provide shiftable bearings for the lower roller 32, which bearings, designated 35, are formed in a yoke 36. This yoke slides between the side pieces of the frame 30 and is preferably formed with projecting lugs 37 which extend out into slots 38 in the side pieces. A bolt 39 projects down from the yoke 36 and passes through a cross bar 40. The lower end of the bolt is provided with a wing nut 41, and a compression spring 42 is located between the cross bar and the yoke, so that the yoke is forced yieldingly upward, and thus the rollers 31 and 32 will engage the stamps or strip of tickets between them.

The carrier for the stamps, tickets or other articles, is designated 43. It may have any desired shape. As shown, however, it comprises a vertical receptacle, oblong in cross section, and having a curved upper end or

cover 44 which is hinged to the body of the receptacle. It also has a hinged door 45 which closes the side of the receptacle. The upper end of the receptacle is formed with the outwardly extending lip 46 whose upper surface is in alignment with the upper surface of a delivery plate 47 supported upon the frame 30. The cover 44 is provided with the extension 48 forming the upper face of the delivery slot, or in other words, covering the delivery plate 47 but spaced therefrom sufficiently to permit the passage of the strip of stamps or tickets to the delivery rolls 31 and 32.

The stamps, tickets or other articles are intended to be placed within the receptacle 43 in a folded condition. In the illustration the receptacle is shown as of sufficient depth to permit the stamps to be folded, three in each length or fold. The stamps or tickets are to be made in a strip of any desired length and are to be folded as above described together with a strip of waxed paper to keep the stamps from sticking. It will be obvious also that any number of strips might be folded together and placed within the receptacle 43 so that two or more stamps might be delivered upon one actuation of the machine. The reason for having the strip folded is that I find in practice that the folding of the strips avoids friction, and the cover of the stamp compartment or ticket compartment is made half round for the same purpose and permits the free delivery of the stamps and avoids the likelihood of the projecting folds of the stamps or tickets contacting with the top of the receptacle.

The locking means for normally preventing the actuation of the machine without the previous deposit of a prescribed coin comprises a locking arm or lever 50 which is pivoted to the upper ends of the triangular frames 9, the locking arm being pivoted between said frames and immediately over the locking wheel 10. The forward end of the locking arm 50 is provided with the downwardly depending T-shaped locking bar 51, and the forward end of the arm 50 is weighted by a weight 52 which will act to throw down the forward end of the arm so that the bar 51 will extend into the notches 11 so that the wheel 10 is prevented from any rotation until the locking arm has been operated to raise the bar from the notch. The rear end of the locking arm 50 is provided at its extremity with the V-shaped chute 53. The rear end of the arm and the chute extends into the space between two opposed guides 54. A slot 55 located toward the lower ends of these guides and extending into the space between them, passes through a partition 56 and opens adjacent to a suitable coin receptacle 57.

Each triangular frame 9, at its apex, is provided with the downwardly extending

slot 60 in which the projecting ends of the T-shaped locking bar 51 project and by which the locking bar is guided in its vertical movements. Each of the frames 9 has 5 upwardly projecting from it the posts 61 which are provided with the upwardly projecting pins 62 adapted to detachably support a removable guiding chute 63. This chute is V-shaped in cross section. Its rear 10 end is adapted to project over, or in other words, to overlap the chute 53 so that a coin passing upon the guide 63 will drop into the movable chute 53. The forward end of the chute 63 has upwardly and forwardly 15 projecting wings 64. Attached to the forward end of the chute 63 is the downwardly projecting plate 65 which at its lower end has the inwardly turned lips 66 adapted to engage with the posts 61, thus permitting the 20 chute 63 to be detached or to be raised or lowered and adjusted to suit the movements of the movable chute 53 and properly receive the coins from the coin-introducing chute 70.

The coin chute 70 comprises two opposed 25 plates 71 and 72. The plate 71 is solid, while the plate 72 is cut away to form a side opening 73. A longitudinally extending bar 74 is mounted between the plates 71 and 72 immediately beneath the square opening 30 73 and forms a floor therefor so that coins supported thereon will topple over through the opening 73 and will not actuate the machine.

Pivottally mounted on the inside face of 35 the casing 2 is the weighted arm 75. This, at one end is provided with the adjustable weight 76 and at the other carries a laterally projecting plate 77. The plate 72 is slotted at its forward end to receive the arm 40 75. The projecting plate 77 on the end of the arm fills the space between the two plates 71 and 72. The weight 76 acts to raise the opposite end of the arm 75 so that its projecting portion 77 is supported on a 45 level with the lower end of the coin slot 3 and on a level with the bar 74. The weight 76 is adjusted so that it will be counterbalanced by a coin of the proper denomination, but will not be counterbalanced by a lighter 50 coin. Thus, any lighter coin which is placed within the slot 3 will not depress the plate 77 but will be guided thereby to the bar 74 and will topple out of the opening 73. A coin of the proper weight, however, will depress the arm 75, and the coin will be lowered to such position that it will reach the runway 78 formed at the lower edges of the plates 71 and 72. Mounted in the extremity 55 of this runway is the magnet 79. The outer end of the chute 63 is spaced from the chute 70 a sufficient distance so that a slug or other metallic blank attracted by the magnet 79 will drop downward between the chute 70 and the guiding chute 63. A genuine coin, 60 however, as for instance a nickel or a cent,

will acquire sufficient momentum in rolling down the chute 70 so that it will jump the gap between the inner end of the chute 70 and the outer end of the chute 63 and thus will be guided down into the chute 53.

It is of course necessary in devices of this kind to provide means for preventing any attempt at actuating the vending apparatus when the commodity to be vended has been exhausted. To this end, I provide a spindle 75 80 pivoted in bearings on the inside of the casing adjacent to the coin slot 3. This spindle has projecting from it and into the coin slot a T-shaped arm 81. Projecting oppositely from the spindle and into the casing 80 is the arm 82. Against this arm operates a spring 83 which acts to normally turn the spindle upon its bearings so that the T-shaped portion 81 will be shifted into a recess formed in the side of the coin slot so 85 that it will be out of the way of the coin when inserted. Connected to the extremity of the arm 82 is a cord 84 which passes over an eye or pulley 85, then extends to an eye or pulley 86 upon the rear wall of the case 90 and then depends downwardly through an eye 87. The lower end of the cord, after passing through the eye 87, is conducted into the stamp compartment 43, and the end of the cord is attached to a blank stamp or 95 blank ticket attached to the last one of the stamps or tickets contained within the stamp or ticket receptacle. Attached to the cord 84 is a weight 88 having a link 89 at its upper end. A pin 90 projects out from the 100 rear wall of the case upon which the weight is adapted to be hung. The weight, when so hung, upon the pin, is entirely clear of the bottom of the case.

The operation of this portion of my invention will be evident. When the last stamp, ticket or other article has been vended, the cord 84 will be pulled sufficiently to draw the weight 88 off from the pin 90. The weight will thus fall, and through the cord 105 84 will retract the arm 82, thus throwing the T-shaped bar 81 outward and blocking the coin slot, thus preventing the insertion of a coin. When the stamp receptacle is once more filled, it is only necessary to lift the 110 weight 88 and hang it once more upon the pin, of course previously attaching the end of the cord to the blank at the extremity of the strip of stamps or tickets.

As a means of preventing the lifting of 120 the locking arm 50 sufficiently to permit the actuation of the wheel 10 until a coin or coins of sufficient weight have been deposited, I provide the rear end of the locking arm with the projecting screw-threaded rod 125 91 upon which is screwed the adjustable weight 92. By adjusting this weight upon the screw-threaded rod, the locking arm may be very delicately counterbalanced so that it will only tip or fall upon the deposit of a 130

coin of the proper weight or of a plurality of coins which together make up the proper weight. As a further means to this end and preventing the fall of the locking arm to its 5 final position until the deposit of the second coin (where a plurality of coins are required), I provide the pivoted counterbalanced supporting arm 93. This, at its outer extremity, is provided with a hook 94 adapted to engage with the locking arm when the latter is depressed to a proper degree. The middle of the arm 93 is pivoted upon a bearing formed on one of the frames 9, and the rear end of the arm is provided with the 10 weight 95. A pin 96 normally projects over the frame 9 to support the weight.

The operation of my invention is as follows: The parts being in their locked position and the stamp or ticket receptacle being 20 filled with folded tickets or stamps, a coin is deposited in the coin slot. If it is a coin of the required dimension, it will pass through the coin slot and will be shot into the guiding chute 63 from which it will be delivered 25 into the movable chute 53. If the coin is of sufficient weight, it will counterbalance the locking arm, and the outer end of the locking arm will descend. As it descends to the full extent, the T-shaped locking bar 51 will 30 be raised partially out of the notch in the wheel 10. As soon as the locking bar has been raised sufficiently from the notch, the knob 5 may be rotated. This will draw down upon the chain 23 operating the step-by-step ratchet wheel which will rotate the 35 shaft 7 to a definite extent, or until the next notch in the wheel 10 is reached. As the shaft rotates, the rollers 31 and 32 will be rotated, drawing out one or a plurality of 40 tickets from the receptacle and delivering them at the delivery slot 4 where they may be torn off from the body of the strip. The rotation of the shaft 7 rotates the wheel 10, and the curved faces of the teeth 12 will act 45 to lift the locking bar 51 so as to permit the easy rotation of the wheel. When the next notch is reached, of course the locking bar drops into it, for by this time the movable chute has reached the slot 60 and the coin 50 has dropped out into the coin receptacle.

I do not wish to be limited to the use of a casing or box for inclosing the stamps or tickets to be sold, as it will be obvious that I might use a reel or other device upon which the strip of stamps is mounted and from 55 which it may be drawn off. I prefer, however, the form of stamp or ticket receptacle shown, as I believe that there is less friction incident to its use than there is where a reel 60 is used.

I do not wish to be limited to the details 65 of the coin-receiving and testing portion of my device above described, as it is obvious that other mechanism may be used for receiving the coin and testing it.

My apparatus is simple, cannot easily get out of order, will only operate upon the deposit of a required coin, and may be adapted for use with one coin or a plurality, as required.

Having thus described the invention, what is claimed as new is:—

1. A coin-operated vending mechanism for articles on strips, including a case, a shaft mounted therein, a gear wheel on the 75 shaft, discharging mechanism driven from said gear wheel, a ratchet wheel on the shaft, an arm rotatably mounted on the shaft adjacent to the ratchet wheel, a pawl mounted on the arm, engaging with the ratchet wheel, 80 a handle exterior to the case, a connection between said handle and the arm, a locking wheel mounted on the shaft and having a series of radial notches, a counterbalanced lever pivoted adjacent to the circumference 85 of the wheel, a locking bar carried by the lever, engageable in any one of the notches, a chute-like receptacle adapted to receive a coin carried on the end of the lever, and a guide in which the outer end of the receptacle moves, the lower portion of said guide being provided with a coin-receiving slot with which said receptacle will register 90 when the locking lever is moved to its lowest position.

2. In a vending mechanism, a case, a shaft mounted therein, means whereby articles may be vended upon a rotation of the shaft through a definite distance, a handle on the exterior of the case, mechanism whereby an actuation of the handle shall cause a definite rotation of the shaft, a locking wheel on the shaft having a series of radial notches, a counterbalanced locking lever pivoted adjacent to the wheel and having a locking bar 100 entering the notches, a coin-receiving chute-like receptacle carried on the end of the lever, and a guide in which said receptacle moves, closing the end of the receptacle, and a coin-receiving slot at the lower end of the 105 guide with which said receptacle registers when the lever has been moved to its lowest position.

3. In a vending mechanism, a case, a shaft mounted therein, article-discharging mechanism connected to the shaft to be operated upon a rotation thereof, a handle exterior to the case, mechanism actuated by the handle whereby the shaft may be rotated a certain definite distance, a locking wheel on the shaft having a series of radial notches, a counterbalanced locking lever pivoted adjacent to the wheel, a coin-receiving chute-like receptacle carried on the outer end of the locking lever, a guide in which said receptacle moves and closing the open end thereof, said guide having a coin-receiving slot at its lower end with which the receptacle will register when the locking lever is moved to its lowest position, a rod pivoted 115 120 125 130

adjacent to the locking lever, one end of said rod being so formed as to be engaged by the locking lever as it moves downward, the other end of the rod being provided with 5 a counterweight, and a stop for preventing the unweighted end of the rod from engaging with the locking lever when the latter is in its uppermost position.

4. In a vending mechanism, a shaft, discharging mechanism connected to the shaft to be actuated upon a rotation of the shaft, a handle, mechanism engaged by the handle for rotating the shaft in one direction to a definite distance, a locking wheel on the 15 shaft having a series of radial notches, the teeth formed between said notches having inclined faces, a locking lever pivoted adjacent to the shaft, a locking bar carried by the lever and intersecting with the notches, 20 a receptacle on the end of the locking lever adapted to receive a coin to counterbalance the locking lever to depress the same to raise the locking bar from the notches and permit the actuation of the machine, and means 25 whereby the coin may be discharged from the receptacle.

5. In a vending mechanism, a rotatable shaft, discharging mechanism connected to the shaft to be turned upon a rotation thereof, a handle exterior to the case, mechanism connecting the handle with the shaft, whereby the latter shall be rotated by an actuation of the handle, a locking wheel having a series of radial notches, a frame 30 located on each side of the locking wheel and having notches adapted to coincide with the notches in the wheel, a counterbalanced locking lever pivoted in said frame, a transversely extending locking bar on the lever, 35 engageable in any one of the notches, a chute-like receptacle on the outer end of the lever, and a guide in which said receptacle moves, said guide having at its lower end a coin slot with which the receptacle is 40 adapted to register when the lever has been moved to its lowest position.

6. A vending mechanism for articles on strips, including a case, a shaft mounted therein, a gear wheel on the shaft, discharging mechanism operated from said gear wheel, a handle exterior to the case, mechanism whereby the shaft may be rotated a definite distance upon the actuation of the handle, a locking wheel on the shaft having 50 a series of radial notches, a pivoted locking lever having a bar engaging with any one of the notches in the wheel, a chute-like receptacle on the outer end of said receptacle, a coin-receiving chute, and an intermediate

chute mounted between the coin-receiving 60 chute and the chute-like receptacle and spaced from the former whereby a coin may be guided from the coin chute to said receptacle to actuate the locking lever.

7. In a vending mechanism for articles 65 on strips, a casing having a coin slot, a device normally held away from but adapted to be moved into a position to close the coin slot, a weight, a cord connecting the weight with the device, a support for the weight 70 so arranged that when the weight is supported thereon, said cord shall be slack, and means connecting the weight with the last end of the strip, whereby the weight may be pulled from its support and allowed to 75 fall upon a movement of the last end of the strip.

8. In a vending mechanism for articles 80 on strips, an outer casing having a coin slot, an inner receptacle for said articles 85 having a delivery mouth, a bar normally held away from but adapted to be moved into a position to close the coin slot, a weight, a cord connecting the weight with the bar, a projecting support for the weight 90 on which the weight is adapted to be hung and so located that the cord from the weight to the said bar shall be slack, and a cord extending from the weight into said article receptacle and there attached to the last end 95 of the strip, whereby when said last end of the strip is moved, the weight will be drawn from engagement with the support and allowed to fall, thereby moving the said bar into the coin slot.

9. In a vending machine, an outer casing, a rotatable shaft, discharging mechanism connected to the shaft, a ratchet wheel on the shaft, an arm projecting from the shaft and radially mounted thereon, a pawl on the 100 arm engaging with the ratchet wheel, a radial handle mounted exterior of the casing and extending into the same, a winding drum actuated by the handle, a flexible connection from the winding drum to said 105 pawl-carrying arm, counterbalanced locking mechanism normally preventing the rotation of the shaft, and means whereby, upon the deposit of a coin, said locking mechanism shall be operated to permit the rotation of 110 the shaft.

In testimony whereof I affix my signature in presence of two witnesses.

HENRY D. EBERT. [L.S.]
